UNITED STATES PATENT OFFICE

LEONARD WOODS, OF ST. LOUIS, MISSOURI

SELF-SUPPORTING HOSE

Application filed June 6, 1929. Serial No. 368,803.

This invention relates to certain new and useful improvements in self-supporting hose, the peculiarities of which will be hereinafter fully described and claimed.

- 5 The main objects of my invention are to provide a hose, stocking or other close-fitting covering for the foot and leg, usually knit or woven, that will maintain its adjusted position on the leg without garter, suspender 10 or other independent means outside of itself; secondly, to provide a self-contained stiffening strip adapted to be removed when such a covering is washed; and thirdly, to provide means to hold said stiffening means detachably in located position relative to said leg covering.

In the accompanying drawing in which like reference numerals indicate the parts referred to in this specification,

- 20 The figure represents a hose with my improvements applied thereto.

Referring to the drawing, the numeral 1, designates a hose of the short style for example which is usually more difficult to maintain in adjusted position on the leg of the wearer.

- In the leg of said hose are provided one or more longitudinally disposed passages 2 extending from the portion of the sides near 30 the ankle joint of the wearer, upward to the top of the leg portion of said hose. These passages are formed by an inner wall 3 thus doubling the knit or woven fabric for a convenient width (such as $\frac{3}{4}$ ") to correspond with that of stiffening strips 4. These are made of pyralin ivory, whalebone, metal, or other suitable material having some flexibility to conform to the wearer's leg, yet stiff enough when enclosed in said passages adjacent the leg of the wearer, to hold up the top 5 of the hose by reacting pressure on the bottom of said strips against the lower end 6 of said passages (or elsewhere) as indicated in the figure.

- 45 The lower end of each strip is preferably at or slightly above the ankle joint, so that foot movement centering at the ankle joint, will not appreciably affect the said strips.

- In the figure, my stiffening strips are of 60 such material and shape as allow of perma-

nent location in corresponding passages. If desired however, these V-shaped strips may be detachably mounted as above described. Thus a cross slit 10' in the inner wall near the bottom of the passage as indicated, will allow insertion of the strips into the passages without the slit appearing on the outside of the hose, and the reactionary pressure will be exerted upward diagonally to the top from the point of the V on each side.

I claim:

1. The combination with a hose leg having double wall side portions of the fabric forming V-shaped connected passages diverging from the ankle to the top and having a transverse slit in the inner wall near one end, of a plurality of stiffening strips insertable through said transverse slit into both said passages and hidden by stretching the hose fabric over the projecting end of each strip 70 so that said strips will bear on both ends of the passages and be detachably secured therein, substantially as described.

2. The combination with a hose leg having double wall side portions forming V-shaped connected passages diverging from the ankle to the top and having a transverse slit at the junction near the ankle, of double strips forming corresponding V-shaped stiffening means longitudinally disposed in said passages and insertable through said slit, substantially as described.

In testimony whereof I have affixed my signature.
